UNITED STATES PATENT OFFICE.

CHARLES BOSWORTH, OF BROOKLYN, NEW YORK.

DESIGN FOR A PICTURE-FRAME MOLDING.

SPECIFICATION forming part of Design No. 25,217, dated March 3, 1896.

Application filed January 31, 1896. Serial No. 577,628. Term of patent 31 years.

To all whom it may concern:

Be it known that I, CHARLES BOSWORTH, a citizen of the United States, and a resident of Brooklyn, in the county of Kings and State 5 of New York, have invented and produced a new and original Design for Picture-Frame Moldings and the Like, of which the following is a specification, reference being had to the accompanying drawing, forming part thereof.

10 The essential features of my design consist in the configuration of the frame and the surface ornamentation thereon composed of conventionally-represented leaves, substantially as illustrated herein.

15 The ornamentation of the moldings A and B is as follows, which in the case of the molding A consists of concave leaves *b*, conventionally represented, and the flowers or bunches of flowers *c* and the foliated figures 20 or ornaments *d* arranged thereon, as shown in the accompanying drawing, all of which are in relief, the concave and conventionally-represented leaves running along and parallel with the sides of the frame or molding. The 25 surface of the molding B is ornamented with a line of conventionally-represented leaves *e* and the foliated figures *g*, arranged substantially as shown in the drawing.

At the corner or corners of the frame or 30 molding there is an ornamentation, as at D,

with the foliated ornaments or figures placed therein, as shown at *h*. The ornament *D*, which is concave, represents a bunch of radiating leaves which project upwardly and inwardly toward the center of the frame or molding. The bunch of radiating leaves enables the concave leaves which connect the line of conventionally-represented leaves and flowers and foliated figures to terminate with good effect at the circular or more or less circular leafy representation at the corner, giving point to the foliated ornaments placed in the circular or partly circular leafy representation at the corner or corners.

The edge of the molding is ornamented, as 35 shown at *k*, with an unbroken line of foliated figures.

What I claim, and desire to secure by Letters Patent, is—

The design for a molding for picture-frames, 50 and the like, substantially as herein shown and described.

Signed at the city of Brooklyn, county of Kings, and State of New York, this 24th day of January, 1896.

CHARLES BOSWORTH.
